C. W. QUIN

BALL

Filed July 17, 1922

Inventor
CHARLES W. QUIN

By Attorney
Richard J. Cook

UNITED STATES PATENT OFFICE.

CHARLES W. QUIN, OF CENTRALIA, WASHINGTON.

BALL.

Application filed July 17, 1922. Serial No. 575,688.

To all whom it may concern:

Be it known that I, CHARLES W. QUIN, a citizen of the United States, and a resident of Centralia, county of Lewis, State of Washington, have invented certain new and useful Improvements in Balls, of which the following is a specification.

This invention relates to improvements in balls, and more particularly to a bouncing, slinging and spinning ball, made especially for the amusement of children.

The principal object of the invention is to provide a resilient ball to which a cord, or string, is attached to serve as a means whereby the ball may be thrown, or caused to spin, or whereby the ball may be retained while being bounced.

Other objects of the invention reside in the provision of grooves in the ball wherein the attached cord is placed and in the manner of attaching the cord to the ball.

In accomplishing these and other objects of the invention, I have provided the improved details of construction, the preferred forms of which are illustrated in the accompanying drawings, wherein—

Figure 1 is a perspective view of a ball with cord attached thereto in accordance with the present invention.

Figure 2 is a central, sectional view through the ball, particularly illustrating the manner in which the cord is secured thereto.

Figure 3 is a sectional view on the line 3—3 in Figure 2, showing the position of the cord within the groove in the ball's surface.

Figure 4 is a detail, sectional view illustrating a step in the attachment of the cord to the ball.

Figure 5 is a similar view illustrating the knotting of the end parts of the cord about the looped portion to secure the same.

Referring more in detail to the several views of the drawings, wherein like reference numerals designate the same or like parts—

1 designates a resilient ball, which preferably would be made of rubber, either solid, or hollow as shown, and in any suitable size convenient to be handled by children. Openings 2 and 3 are provided in the walls at points diametrically opposite and a circumferential groove 4 is formed about the

outer surface of the ball, passing through these openings.

Secured to the ball is a cord 5 whereby the ball may be thrown, or caused to spin. The cord is attached to the ball in a manner which is especially important and which is as follows: First the cord is doubled at the center, and the looped end 6 is extended through the ball openings so that the loop extends slightly at one side thereof. The end portions 5^a and 5^b are then drawn about the ball in opposite directions, tightly within the grooves and extended through the loop 6 from opposite sides, as is shown in Figure 4. A knot 7 is then tied to join the strands together just above and about the loop, as shown in Figure 5, whereby the cord is retained tightly about the ball and within the grooves. The outer ends of the cord may be knotted together, as at 8, for better use and handling of the ball.

It is readily apparent that by so attaching the cord to the ball it is impossible for it to come loose therefrom, and that by locating the cord within the grooves, it will not become worn to an extent which might cause it to break.

The ball may be used in several ways; one way being as a slinging ball, another as a bouncing ball and still another as a spinning ball. To sling the ball, the cord 5 is held by the end and the ball whirled about and then the cord is released. For spinning, the cord is twisted and the ball held suspended while it unwinds. For bouncing, the cord may be attached to the hand so that the ball can be retained.

It is apparent that the ball could be used in various other ways to amuse and by making certain colored designs or figures on the ball it would be very attractive and amusing especially to children.

Having thus described my invention, what I claim as new therein and desire to secure by Letters Patent, is:

1. A ball having a diametrical opening and a circumferential groove in its outer surface passing through the ends of said opening and a cord doubled at its center with the looped end thereof extended through said opening and having its opposite ends extended about the ball within said groove and through the loop.
2. A hollow resilient ball having open-

ings in its walls at diametrically opposite sides, and a circumferential groove in its outer surface passing through said openings, a cord doubled at the center, with the 5 looped end extended through said openings and at one side of the ball, and having its opposite ends extended about the ball in

opposite directions within said groove and through said loop, and knotted together about the loop and at their outer ends.

Signed at Seattle, Washington, this 11th day of July, 1922.

CHARLES W. QUIN.
